US00D991940S

(12) **United States Design Patent** (10) Patent No.: **US D991,940 S**
Monsalve et al. (45) Date of Patent: **** Jul. 11, 2023**

(54) **MONITOR ARM**(71) Applicant: **Humanscale Corporation**, New York, NY (US)(72) Inventors: **Fabian Monsalve**, New York, NY (US); **Ross Velazquez**, New York, NY (US); **Jacob Glickstein**, Golden Valley, MN (US)(73) Assignee: **Humanscale Corporation**, New York, NY (US)(**) Term: **15 Years**(21) Appl. No.: **29/851,290**(22) Filed: **Aug. 26, 2022****Related U.S. Application Data**

(63) Continuation of application No. 29/781,576, filed on Apr. 30, 2021, now Pat. No. Des. 965,000, which is a continuation of application No. 29/642,593, filed on Mar. 30, 2018, now Pat. No. Des. 920,986.

CLAIM

We claim the ornamental design for a monitor arm, as shown and described.

DESCRIPTION

FIG. 1 is a right front perspective view of a monitor arm; FIG. 2 is a left rear perspective view of the monitor arm of FIG. 1; FIG. 3 is a front view of the monitor arm of FIG. 1; FIG. 4 is a rear view of the monitor arm of FIG. 1; FIG. 5 is a left view of the monitor arm of FIG. 1; FIG. 6 is a right side view of the monitor arm of FIG. 1; FIG. 7 is a top view of the monitor arm of FIG. 1; and, FIG. 8 is a bottom view of the monitor arm of FIG. 1. The evenly-spaced broken lines in FIGS. 1-8 illustrate portions of the monitor arm that form no part of the claimed design. The dash-dot-dash broken lines in FIGS. 1-6 illustrate the boundary of the claimed design which forms no part thereof.
